CLAIM

The ornamental design for a food support, as shown and described.

DESCRIPTION

FIG. 1 is a top, front, right side perspective view of a food support showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a top, front, right side perspective view of a second embodiment of that shown in FIG. 1;

FIG. 7 is a top plan view thereof;

FIG. 8 is a bottom plan view thereof;

FIG. 9 is a left side elevational view thereof; and

FIG. 10 is a rear elevational view thereof.

FIG. 6

FIG. 7

FIG. 8

FIG. 9

FIG. 10
